US00D983463S

(12) **United States Design Patent** (10) Patent No.: **US D983,463 S**
Chen (45) Date of Patent: **** Apr. 11, 2023**

(54) **PET FEEDER**

(71) Applicant: **Fuzhou Boweier Trading Co., Ltd.**,
Fujian (CN)

(72) Inventor: **Bo Chen**, Fujian (CN)

(73) Assignee: **Fuzhou Boweier Trading Co., Ltd.**,
Fuzhou (CN)

(**) Term: **15 Years**

(21) Appl. No.: **29/868,852**

(22) Filed: **Dec. 14, 2022**

(51) LOC (14) Cl. **30-07**

(52) U.S. Cl.

USPC **D30/122**

CLAIM

The ornamental design for a pet feeder, as shown and described.

DESCRIPTION

FIG. 1 is a top, front, left side perspective view of a pet feeder, showing my new design;
FIG. 2 is a bottom side perspective view thereof;
FIG. 3 is a front elevational view thereof;
FIG. 4 is a back elevational view thereof;
FIG. 5 is a left side elevational view thereof;
FIG. 6 is a right side elevational view thereof;
FIG. 7 is a top plan view thereof; and,
FIG. 8 is a bottom plan view thereof.

1 Claim, 8 Drawing Sheets
